US0D1022094S

(12) **United States Design Patent** (10) Patent No.: **US D1,022,094 S**
(45) Date of Patent: ** Apr. 9, 2024

(54) **GOLF CLUB GRIP**

(71) Applicant: **PARSONS XTREME GOLF, LLC**,
Scottsdale, AZ (US)

(72) Inventors: **Daniel C. Kirtley**, Scottsdale, AZ (US);
Raymond C. Gresalfi, Oyster Bay
Cove, NY (US)

(73) Assignee: **PARSONS XTREME GOLF, LLC**,
Scottsdale, AZ (US)

(**) Term: **15 Years**

(21) Appl. No.: **29/844,490**

(22) Filed: **Jun. 29, 2022**

(51) LOC (14) Cl. **21-02**

(52) U.S. Cl.

USPC **D21/756**

(58) **Field of Classification Search**

Primary Examiner — Mitchell I. Siegel

(57) **CLAIM**

The ornamental design for a golf club grip, as shown and described.

DESCRIPTION

FIG. 1 is a top perspective view of a golf club grip;
FIG. 2 is a bottom perspective view of the golf club grip of FIG. 1;
FIG. 3 is a front elevational view of the golf club grip of FIG. 1;
FIG. 4 is a rear elevational view of the golf club grip of FIG. 1;
FIG. 5 is a top view of the golf club grip of FIG. 1;
FIG. 6 is a bottom view of the golf club grip of FIG. 1;
FIG. 7 is a right side view of the golf club grip of FIG. 1;
and,
FIG. 8 is a left side view of the golf club grip of FIG. 1.
